CENTRIFUGAL PUMP

Hanns Hornschuch, Easton, Pa., assignor to Ingersoll-Rand Company, New York, N. Y., a corporation of New Jersey

Application March 20, 1942, Serial No. 435,444

6 Claims. (Cl. 103—115)

This invention relates to pumps, and more particularly to pumps of the centrifugal type.

One object of the invention is to increase the ability of a centrifugal pump to operate at high suction lift or at low net positive suction head without necessitating the operation of the pump at reduced speeds.

Another object is to assure the delivery of liquid to a pump impeller in a state best suited to assure maximum impelling effect upon the liquid.

Other objects will be in part obvious and in part pointed out hereinafter.

In the drawings accompanying this specification and in which similar reference numerals refer to similar parts,

Figure 1 is an elevation, partly in section, of a centrifugal pump constructed in accordance with the practice of the invention,

Figure 2 is a view similar to Figure 1, although somewhat enlarged, showing the impelling element of the pump in section,

Figures 3 and 4 are perspective views of the pump impellers, and

Figures 5 and 6 are views similar to Figure 2 showing modified forms of the invention.

Referring to the drawings and at first more particularly to Figures 1 to 4 inclusive, 20 designates a centrifugal pump comprising a casing 21 having an impeller chamber 22 and an inlet passage 23 for conveying liquid to the impeller chamber. The casing also has an outlet passage 24 for the discharge of liquid from the impeller chamber, and a head 25 is secured to the casing 21 by bolts 26 to form a closure for one end of the impeller chamber 22.

The head 25 is provided with a horizontal bore 27 to receive, among other elements, a shaft 28 that extends through the hub 29 of an impeller 30 arranged in the impeller chamber. A sleeve 31 encasing the shaft 28 and rotatable therewith abuts the hub 29, and the end of the sleeve 31 adjacent the hub 29 cooperates with the reduced portion 32 of the shaft upon which the impeller is mounted to define a chamber for the reception of packing material 33 intended to exclude liquid from the cooperating surfaces of the shaft 28 and the sleeve 31.

The bore 27 is of sufficiently larger diameter than the sleeve 31 to receive packing material 34 which is disposed about the sleeve 31 for preventing leakage of liquid through the bore 27 exteriorly of the sleeve. The inner end of the packing material 34 seats against an annular wearing piece 35 inserted in the bore 27. The im-

peller 30 and which may be termed the main impeller is secured to the shaft 28 by clamping its hub against the sleeve 31 with a nut 36 on the outer extremity of the reduced portion 32 of the shaft.

In order to avoid subjecting the packing members 33 and 34 to the high pressure of the liquid in the impeller chamber 22 the impeller is provided on its end surface with radially extending vanes 37 to eject liquid from the space between the impeller and the head 25 and thereby maintains a zone of low pressure adjacent the end of the bore 27.

In accordance with the practice of the invention, the liquid pumped by the impeller 30 is delivered thereto by a second or booster impeller 38 also arranged in the impeller chamber 22. The booster impeller 38 is capable of free rotation relatively to the main impeller and is mounted, for such rotation, upon an end portion 39 of the shaft 28, the shaft having a sleeve 40 to provide a bearing surface for bushings 41 extending into the opposite ends of the hub 42 of the impeller 38.

A seat, in the form of a washer 43, clamped against a shoulder 44 at the juncture of the reduced and end portions 32 and 39, respectively, of the shaft is provided for the inner end of the sleeve 40. A cap nut 45 threaded upon the extremity of the end portion 39 of the shaft secures the sleeve 40 and the washer 43 in assembled positions and overlies the end of the outermost bushing 41 to serve as an abutment therefor. The sleeve 40 is of such length and the cap nut 45 and the washer 43 are, in consequence, so spaced with respect to each other that the impeller 38 is capable of rotating freely upon the shaft without hindrance from the elements restraining it from endwise movement.

In the form of the invention illustrated, the eye 46 of the impeller 30 is of frusto-conical shape and its bottom 47 is defined by the inner wall 48 of the impeller 30. Owing to this arrangement the inner ends 49 of the vanes 50 of the impeller 30 lie at an acute angle with respect to the axis of the shaft and the inner end portions of the water-ways in the impeller are only slightly curved as indicated at 51 so that there will be only a small degree of deviation of the course of the liquid within the impeller 30. The vanes 50 may be of any known design to assure desired impelling surfaces but are preferably curved as indicated more particularly in Figure 4 of the drawings.

It is in the booster impeller 38 that the initial

transition from axial flow to radial flow of the liquid takes place. The vanes 52 of said impeller are, as indicated more particularly in Figure 3 of the drawing, of the curved type. They extend into the radial plane of the eye of the main impeller, and operate to deliver the liquid to the main impeller in a whirling body. As a preferred arrangement the inner or discharge ends 53 of the vanes 52 are separated by a suitable space 54 from the ends 49 of the vanes 50 of the main impeller in order to assure a full supply of liquid to the main impeller in all relative positions of the impellers.

The force serving to cause rotation of the booster impeller 38 is derived from the impeller 30. To this end the main impeller is provided on the end surface confronting the booster impeller with a plurality of radially extending ribs 55 for imparting rotary motion to the liquid in the adjacent portion of the impeller chamber 22. The force thus generated acts against the side of a flange 56 on the periphery of the impeller 38 and lying closely adjacent the ribs 55. The side of the flange 56 confronting the ribs 55 may, as shown, also be provided with radially extending ribs 57 to assure the utmost utilization of the force or thrust of the rotating body of liquid between the impeller 30 and the flange 56.

The liquid serving the function of transmitting driving force from the impeller 30 to the impeller 38 is cast centrifugally into the impeller chamber by the ribs 55 which cause a constant circulation of liquid between the impeller 30 and the flange 56. Such liquid, in the present instance, is derived in part from the space 54 which communicates with the space between the impeller 30 and the flange 56 through an annular groove 58 in the inner end of the rim 59 of the impeller 38. The groove 58 is of considerable depth to accommodate an annular flange 60 on the impeller 30, and ample clearances exist between the annular surfaces of the groove 58 and the flange 60 so that liquid will flow freely through the groove.

Suitable balancing means are provided to assure against undue end thrust of the booster impeller 38 in the direction of the inlet passage 23. To this end the booster impeller is provided with a cylindrical extension 61 on the end of the rim 59. The extension 61 extends rotatably into an annular groove 62 in the inner surface of a liner 63 defining the inlet passage directly adjacent the booster impeller 38.

The extension 61 has a free running fit in the groove 62 so that liquid under pressure may flow freely from the impeller chamber 22 into the bottom of the groove 62 to act against the end of the cylindrical extension for performing its balancing function. An outlet is provided for liquid from the groove 62 by passages 64 in the extension 61 and the rim 59 and leading into the groove 58. Thus, some of the liquid impelled by the ribs 55 for driving the booster impeller 38 is also derived from the impeller chamber 22.

The operation of the device is as follows: At the beginning of rotation of the main impeller 30 the force generated by the ribs 55 may be insufficient to overcome the resistance of the booster impeller. But upon acceleration of the impeller 30 this force will increase until it reaches a critical value sufficient to set the impeller 38 in motion. As the speed of the impeller 30 increases the impeller 38 will also accelerate until it attains the maximum speed consistent with the force serving to drive it.

Owing to the slippage that must naturally result between the driving and driven elements the impeller 38 will, of course, operate at a somewhat lower speed than the main impeller. The extent of this differential in speed will vary in accordance with variations in size of the area on the booster impeller against which the force is applied for driving it, as will be readily understood.

During this operation of the pump the liquid flowing through the inlet passage 23 will first be handled by the comparatively slow moving impeller 38 so that a whirling motion will be imparted to it for delivering it as a whirling body to the main impeller which will impress additional velocity to the liquid.

In practice, it has been found that, owing to the use of the booster impeller arranged and driven in the manner hereinbefore described, a centrifugal pump of a given design may operate with increased efficiency at a considerably greater suction lift or at lower positive suction head and without necessitating reduced rotative speed of the impeller than would be the case if the liquid were pumped only by the main impeller. It has further been found that these advantages may be obtained without necessitating an appreciable expenditure of additional power for driving the pump.

The modified form of the invention shown in Figure 5 differs from that previously described principally in that the impellers are mounted upon separate shafts arranged coaxially with respect to each other. The impeller 30 is accordingly mounted upon the end of the shaft 26 which has threaded thereon a nut 36 for clamping the impeller upon the shaft. The impeller 38 is secured, in like manner, by a nut 65 upon a reduced end portion 66 of a shaft 67.

The impeller 38 is suitably keyed to the shaft 67 and said shaft extends through a packing element 68 in the end of the casing 21 and into a bearing cage 69 exteriorly of the casing 21. Suitable anti-friction bearings 70 are arranged in the ends of the cage 69 for the shaft 67 and the shaft preferably has shoulders 71 to abut the inner races of the anti-friction bearings for preventing axial movement of the shaft.

Although the shaft 67 is shown as terminating within the bearing cage 69, it will be readily understood that the shaft could be extended through the outer end of the bearing cage for connection with a driving motor whereby the speed of the impeller 38 could be definitely controlled to assure best pumping results.

In the modified form of the invention shown in Figure 6 the casing 21 is provided with a removable head 72 on the inlet side of the pump. The inlet passage 23 is, moreover, located within the head 72 and the inner end of the head forms a bounding surface for the impeller chamber 22.

In this form of the invention the main impeller designated 73 is open on one side and a flange 74 on the periphery of the booster impeller 38 serves as a shroud for the open side of the main impeller. The flange 74 is disposed closely adjacent the open side of the impeller 73 so that its inner surface 75 will be subjected to frictional contact with the liquid in the main impeller and moving rotatively therewith for driving the booster impeller 38.

The booster impeller 38 is shown as being mounted rotatively upon an end portion 76 of the shaft 77 carrying the main impeller, and a collar 78 on the shaft 77 lies between the hubs

of the impellers to clamp the impeller 13 against the sleeve 31 and to act as an abutment for the innermost of the bushings 41 in the booster impeller.

I claim:

1. A centrifugal pump, comprising a casing having an impeller chamber, a main impeller rotatable in the impeller chamber, a second impeller in the said impeller chamber positioned to discharge directly into the eye of the main impeller, and flange means on the said second impeller located adjacent the side of the main impeller and having means on the side thereof to absorb power from the fluid pumped by the main impeller for effecting rotation of the said second impeller.

2. A centrifugal pump, comprising a casing having an impeller chamber, an impeller in the impeller chamber, a shaft in the casing for the impeller, means for locking the impeller to the shaft, and a second impeller supported by and freely rotatable upon the said shaft to deliver liquid to the first mentioned impeller fluid-impelling means on the side of the main impeller, and flange means on the second said impeller and having means on a side thereof presenting radially extending surfaces to absorb power from the fluid pumped by the said fluid-impelling means for effecting rotation of said second impeller.

3. A centrifugal pump, comprising a casing having an impeller chamber, a main impeller in the impeller chamber, a second impeller for delivering liquid to the main impeller, blade means

on an outer side surface of the main impeller for imparting rotary motion to liquid in the impeller chamber, and blade means on the second impeller subjected to the force of the liquid rotating in the impeller chamber for driving the second impeller.

4. A centrifugal pump, comprising a casing having an impeller chamber, a main impeller in the impeller chamber, ribs on the side of the main impeller to impart a whirling motion to liquid in the impeller chamber, a second impeller in the said impeller chamber to deliver liquid to the main impeller, and a flange on the second impeller arranged adjacent the said ribs and having ribs subjected to the whirling motion of the liquid impelled by the first-mentioned ribs for rotating the second impeller.

5. A centrifugal pump, comprising a casing having an impeller chamber, an open-type impeller in the impeller chamber, a second impeller to deliver liquid to the first mentioned impeller, and means on the second impeller forming a shroud for the open side of the open-type impeller.

6. A centrifugal pump, comprising a casing having an impeller chamber, an open-type impeller in the impeller chamber, a second impeller to deliver liquid to the first mentioned impeller, and a flange on the second impeller forming a shroud for the open-type impeller and being subjected to the liquid passing through the open-type impeller for driving said second impeller.

HANNS HORNSCHUCH.
